SAFETY RAZOR

Louis Frank, Fellows, Calif.

Application April 19, 1944, Serial No. 531,687

4 Claims. (Cl. 30—70)

My invention relates to a safety razor and has for its principal object, to provide a simple practical and inexpensive structure, including a handle, blade holder and blade wherein the holder and blade are constructed and shaped so that the holder will receive and clamp, only those blades which are specifically produced and shaped for use in said holder, thereby overcoming the indiscriminate use of various shaped blades with the holder.

There are at present, on the market, a number of safety razor blade holders which will receive and clamp, many different makes of razor blades, some of which may be of inferior quality and for the protection of manufacturers of high grade safety razors and blades, I propose to provide a holder which will receive only those blades which are produced for complementary use in such holder.

With the foregoing and other objects in view, my invention consists in certain new and novel features of construction and arrangement of parts which will be hereinafter more fully described and claimed and illustrated in the accompanying drawing in which Fig. 1 is a top plan view of one form of my improved razor blade Fig. 2 is a vertical longitudinal section taken through the center of the holder.

Fig. 3 is a perspective view of the two blade clamping plates also showing the upper end of the handle.

Fig. 4 is a section similar to Fig. 2 and showing a modified arrangement.

Fig. 5 is a perspective view of the form of blade used with the form of holders shown in Fig. 4.

Fig. 6 is a perspective view of a further modified form of blade.

Referring by numerals to the accompanying drawing and particularly to the construction illustrated in Figs. 1, 2 and 3, 10 designates the lower member of the holder, which is curved transversely and provided on its longitudinal edges with conventional safety razor teeth 11 and formed in the center of this member 10 is an aperture 12.

Formed in the upper surface of member 10 in longitudinal alignment with aperture 12 are small shallow recesses 13.

The upper member 14 of the holder is crescent shape in cross section equal in length, but slightly shorter than lower member 10 and depending from the underside of said upper member is a centrally arranged threaded stud which passes through aperture 12 in the lower mem-

ber and enters a threaded bore 16, in the upper end of handle 17. Formed in the underface of upper member 14 in alignment with each other and with aperture 20 are small recesses 18, spaced so as to coincide with recesses 13 in member 10 when the parts of the razor are assembled.

Blade 19 is substantially rectangular in shape and formed of wafer thin resilient steel having sharp longitudinal edges 20 and formed in the center of said blade is an aperture 21 for the reception of stud 15 when the blade is positioned in the holder.

Formed in the blade in longitudinal alignment with each other and with aperture 21, are indentations which provide small studs 22, located and spaced so as to enter the recesses 13 and 18 when the razor parts are assembled.

Obviously the number of the recesses 13, and 18, and studs 22 may vary, although as illustrated, I prefer to provide for each of said recesses and studs, two on each side of the stud 15 and aperture 21 and with the members of each pair of studs 22 reversely arranged, i. e., one stud projecting from one face of the blade and the other projecting from the other face.

Thus, when a blade is positioned in the holder, two of the studs 22 are seated in two of the recesses 13 in lower member 10 with the other two studs seated in two of the recesses 18 in upper member 14 and when the handle 17 is screwed onto stud 15, the blade will be firmly clamped between plates 10 and 14.

Inasmuch as the blade engaging faces of the frame member 10 and 14 are devoid of all ribs, stud grooves and the like, it will be impossible to apply and clamp between said members, blades which are especially constructed for co-operative use with such ribbed, studded or grooved members.

In Figs. 4 and 5, I have shown a modified structure wherein the inner faces of the frame plates are provided with registering recesses 25 adapted to receive the heads of studs or rivets 26, on both faces of the interposed blade.

In Fig. 6, the blade is shown indented so as to form two studs 27, with one projecting from each face of said blade. This form of blade may be used with the form of holder seen in Fig. 4.

It is to be noted that in my improved razor blade there is at least one stud such as 22, 26 or 27 projecting outwardly from each face of the blade and thus the latter cannot lie flat upon a surface and such provision is an advantage, inasmuch as it enables the blade to be more readily picked up from a flat surface and

further, air can circulate beneath the blade, thus tending to more rapidly dry the blades after use.

Thus it will be seen that I have provided a safety razor wherein the holder and blade are constructed so that said holder will receive and clamp, only those blades intended to be used with the particular holder, thus preventing the indiscriminate use of blades with the specially formed holder.

My improved safety razor is simple in structure, inexpensive of manufacture and very effective in performing the functions for which it is intended.

It will be understood that minor changes in the size, form and construction of the various parts of my improved safety razor may be made and substituted for those herein shown and described without departing from the spirit of my invention, the scope of which is set forth in the appended claims.

I claim as my invention:

1. In a safety razor, a holder comprising a pair of plates, a blade adapted to be positioned between said plates and pairs of interengaging studs and recesses on the contacting faces of said plates and blade between the centers and ends thereof.
- 5 2. A safety razor as set forth in claim 1 and means including a handle for clamping said plates and blades to each other.
- 10 3. In a safety razor, a holder comprising a pair of plates provided on their adjacent faces with pairs of recesses disposed between the centers of said plates and the ends thereof, a blade adapted to be positioned between said plates and pairs of studs on said blade between the center and ends thereof for engagement in the recesses in said plates.
- 15 4. A safety razor as set forth in claim 3 and with means including a handle for clamping said plates and blades together.

LOUIS FRANK.
